UNITED STATES PATENT OFFICE.

MARY BASSETT HAMACHER AND IGNATIUS McCUTCHAN, OF WINDSOR, MISSOURI.

AUTOMATIC TELEPHONE-RESPONDER.

1,277,572.

Specification of Letters Patent. Patented Sept. 3, 1918.

Application filed November 22, 1916. Serial No. 132,890.

To all whom it may concern:

Be it known that we, MARY BASSETT HAMACHER and IGNATIUS McCUTCHAN, citizens of the United States, residing at Windsor, 5 in the county of Henry and State of Missouri, have invented a certain new and useful Improvement in Automatic Telephone-Responders, of which the following is a specification.

10 Our invention relates to improvements in Automatic telephone responders.

The object of our invention is to provide a novel automatically actuated device for answering a telephone call, in a manner such 15 that the person calling at the other end of the line will hear in his receiver certain predetermined signals or messages as it may be desired to have sent to him. For example, a person calling up a telephone provided 20 with our improvement may receive the message "Mr. Brown will be back at 2 o'clock" or such other message as may be desired to have delivered.

A further object of our invention is to 25 provide a device of the character described which will be simple in construction and not liable to get out of order, and which may be readily operated by an unskilled person.

The novel features of our invention are 30 hereinafter fully described and claimed.

In the accompanying drawings, which illustrate our invention,

Figure 1 is a side view of our improved 35 automatic signaling device shown partly in vertical section and partly in side elevation.

Fig. 2 is a top view of the same, the casing being shown in horizontal section.

Fig. 3 is an end view of the same, the casing being shown in vertical section.

40 Fig. 4 is a vertical sectional view on the line 4—4 of Fig. 1.

Fig. 5 is a fragmental view in side elevation of some of the parts.

Fig. 6 is a cross section on the line 6—6 45 of Fig. 5.

Fig. 7 is a reduced side elevation of the casing.

Fig. 8 is a vertical sectional view taken on the plane of the line 8—8 of Fig. 2.

50 Fig. 9 is a diagrammatic view of the electrical circuits employed in connection with our device.

Similar reference characters designate similar parts in the different views.

55 1 designates an inclosing casing, on the

bottom of which is mounted a base plate 2, from which upwardly extend standards 3, in which is rotatably mounted a horizontal longitudinal shaft 4, Fig. 8, on which is revolubly mounted a head 5 of conoidal shape, 60 which is adapted to receive thereon a cylindrical hollow phonograph record 6, which is provided with a plurality of annular peripheral grooves 7, which are disconnected from each other and each of which is provided 65 with a phonogram, which may comprise any desired message which the operator of the machine may desire to have transmitted to any caller over his telephone line during the absence of the operator. 70

A reproducer 8, of any ordinary type and provided with a stylus 9, Fig. 3, adapted to travel in any one of the grooves 7, is provided with an arm 10, which at its lower end is pivoted and longitudinally slidable on a horizontal bar 11 which is disposed parallel with the axis of the record 6, and which has its ends mounted in two standards 12 which extend upwardly from the base 2. Secured to the arm 10 and extending through a slot 13 in one side of the casing 1 is a finger piece 14, the upper side of which is provided with a tooth 15, which is adapted to enter any one of a row of notches 16, Fig. 7, at the upper side of the slot 13, so as to lock the arm 10 85 releasably from longitudinal movement on the bar 11. 80

The reproducer 8 rests by gravity in the operative position, shown in Fig. 3. By depressing the finger piece 14, the reproducer 90 may be swung upwardly to a position in which the stylus 9 will be disengaged from the record. At the same time, the tooth 15 will be forced out of the notch 16 in which it has rested. The arm 10 carrying the reproducer 8 may then be adjusted lengthwise of the bar 11 to the desired position. The notches 16 are similar in number and spaced apart the same distance as the grooves 7. 95

When the reproducer is in operative position, and the record 6 is revolved, the phonogram in the groove 7 which is engaged by the stylus 9, will operate the reproducer 8. 100

Mounted on the reproducer 8 is a telephone transmitter of any ordinary type arranged to be operated by the reproducer.

In the form shown, the stylus 9 is carried by a lever 17, Fig. 3, pivoted to a weighted bar 18, which is pivoted at one end to the casing of the reproducer 8. Connected to 110

the lever 17 is a small rod 19, which is secured to a diaphragm 20, Fig. 9, of the telephone transmitter. Upon the diaphragm 20 is granulated carbon 21, or some other suitable variable resistance material, upon which rests an electrode 22 connected by a conductor 23 with a battery 24, which is connected to the diaphragm 20 and includes the primary coil or winding of an induction coil, 10 the secondary coil 26 of which is placed in the telephone circuit, which includes the two line wires 27 and 28, which are respectively connected to the opposite ends of the winding 26. The remainder of the circuit is not 15 illustrated as it embodies the ordinary telephone circuit construction, which is well known.

For automatically rotating the shaft 4, there is provided an ordinary flat involute 20 spring 29, one end of which is secured to the shaft 4 and the other end of which is fastened to a rod 30 having its ends mounted in the standards 3.

Secured to the shaft 4 is a collar 31, which 25 is provided with a notch 32 adapted to receive a pawl 33, Fig. 4, which is pivoted to the adjacent end of the head 5 by a screw 34 and which is normally forced against the collar 31 by a spring 35, which is also set 30 cured to the head 5.

The spring 29 is arranged so as to rotate the shaft 4 counter-clock-wise, as viewed in Figs. 3 and 4, thereby turning the head 5 and record 6 in a like direction.

35 The pawl and collar connection between the shaft 4 and head 5 is to permit the shaft 4 to be turned so as to wind the spring 29, without turning the head 5 and record 6. The outer end of the shaft 4 may be squared, 40 as shown, to permit a key or winding crank, not shown, to be attached thereto.

For the purpose of normally holding the head 5 and record 6 from turning, the head 5 at one end is provided with a notch 36, 45 Figs. 4 and 9, which is adapted to receive a locking detent 37 comprising a horizontally slidable solenoid core, which is normally forced into operative position by a coil spring 38, Fig. 8, and which is mounted in 50 the central opening of a solenoid winding 39, the ends of which are respectively connected to conductors 40 and 41, Fig. 9, which are respectively connected to the conductors 27 and 28. The conductor 41 is provided 55 with a pivoted switch or cut-out lever 42, which is shown in the closed position in Fig. 9.

When a pre-determined current, such as 60 a current for ringing the telephone bell passes over the circuit which includes the conductors 27 and 28, if the switch 42 is closed, a portion of the current will pass through the winding 39, thus energizing the solenoid and causing the core 37 to be withdrawn from engagement with the head 5.

The spring 29 will then cause the record 6 to be turned through the intermediary of the head 5 and shaft 4, and the stylus 9 of the reproducer traveling in the groove in which it is located, will be actuated by the phonogram in said groove and will in turn actuate the transmitter diaphragm 20, through the intermediary of the lever 17 and rod 19. The message which is comprised in the phonogram will thus be transmitted in the usual manner by the transmitter, and the person, who is at the other end of the line at the time will receive the message in his receiver as telephone messages are usually received. 70 75 80

In order that the record 6 shall be rotated at the proper speed, the following described mechanism is preferably employed.

Rigidly secured to the shaft 4, see Figs. 5, 6 and 8, is a collar 43, on which is pivoted a lever 44, one arm of which is adapted to strike a pin 45, which is provided on the adjacent side of a spur gear wheel 46 which meshes with a vertical rack 47, Fig. 4, which is vertically slidable and which is secured 90 to the upper end of a vertical rod 48 which is slidable in the upper end of a vertical dash pot 49, preferably containing oil and in which is reciprocatively mounted a piston 50 which is secured to the lower end of 95 the rods 48 and which is provided with a vertical hole 51 which forms a by-pass.

As soon as the shaft 4 begins to revolve, it carries with it the collar 43, and the lever 44 carried thereby engages the pin 45 and turns the spur gear wheel 46 counter clockwise, as viewed in Fig. 4, thereby lifting the rack 47 and the piston head 50, the upward movement of which is resisted by the liquid in the dash pot 49. 100 105

The dash pot, thus, in the usual manner, governs the turning of the shaft 4, so that the latter and the record 6 travels at the required speed.

After the shaft 4 has made nearly one 110 revolution, the free end of the lever 44 strikes a pin 52, thereby swinging the lever 44 so that it becomes disengaged from the pin 45, whereupon the spur gear wheel 46, which is loosely mounted on the shaft 4, is 115 free to revolve, and the rack 47 and piston head 50 will fall by gravity to the initial position shown in Fig. 4. The continued rotation of the shaft 4 will carry the collar 43 and lever 44 to the initial position shown 120 in Fig. 6, at which time the solenoid core 37 will have entered the recess or notch 36, and the head 5 and shaft 4, as well as the record 6 will stop. The pin 52 is secured to one of the standards 3. A spring 53 secured 125 to the collar 43 serves to force the lever 44 to position for engaging the pin 45.

In operating the responder, the operator adjusts the finger piece 14, as before described, so that the stylus 9 of the repro- 130

ducer is located in the groove which contains the phonogram or message that it is desired to have sent to any one who calls up on the telephone during the absence of 5 the operator.

As soon as the ringing current passes over the line, the solenoid winding 39 will be energized, and the core 37 will be withdrawn from the notch 36. The spring 29 will then 10 rotate the shaft 4 and record 6, thereby causing the reproducer to operate the transmitter, upon which the message will be transmitted to the distant station, which is calling at the time, and the person at that station having his receiver at his ear will hear 15 the message which is being transmitted.

As soon as the record has made one revolution, the ringing current over the line having ceased by this time, and the solenoid 20 core 37 being freed from the action of the winding 39, will be forced by the spring 38 into the notch 36, thereby stopping the record in the initial position. The solenoid is unresponsive to the talking current.

25 The apparatus is now in position for another operation.

We do not limit our invention to the structure shown and described, as modifications, within the scope of the appended 30 claims, may be made without departing from the spirit of our invention.

What we claim is:—

1. In an automatic telephone responder, the combination with a rotary phonograph 35 record support, of means for rotating said support, means including a dash-pot for controlling the speed of rotation of said support, an electric circuit including a helix, a magnetizable locking member movable out 40 of locking engagement with said support by said helix, when the latter is energized, means for normally forcing said locking member to the locking position, and means for disconnecting the dash-pot controlling 45 means from said support at the end of each revolution of the support and for connecting the dash-pot controlling means with said support at the beginning of each revolution thereof.

50 2. In an automatic telephone responder, the combination with record supporting means, of means for rotating said record supporting means, a gear wheel rotatable on said supporting means, a lever carried by 55 said supporting means adapted to engage and rotate said gear wheel, means for releasing said lever from said gear wheel after said supporting means has made one revolution, a rack engaging said gear wheel, and a

dash-pot having a plunger secured to and movable with said rack.

3. In an automatic telephone responder, the combination with a rotary record support, means for rotating said support, a gear wheel rotatable on said support, means carried by said support for engaging and carrying with it said gear wheel, means by which said engaging and carrying means is disengaged from said gear wheel during each revolution of said support, a rack meshing 65 with said gear wheel, a dash-pot plunger movable with said rack, and electro-magnetic locking means for controlling the rotation of said record support.

4. In an automatic telephone responder, 75 the combination with a rotary record support, of means for rotating said support in one direction, the support having a notch, a solenoid winding, a solenoid core adapted to enter said notch for holding said support 80 from turning and movable out of said notch by said winding when the latter is energized, means for normally forcing said core into said notch, a pawl carried by said record support, a gear wheel rotatable on said record support and adapted to be engaged by 85 said pawl so as to rotate with said support, a spring for normally forcing said pawl into engagement with said gear wheel, means for engaging said pawl and swinging it out of 90 engagement with said gear wheel once during each revolution of said support, a rack engaging with said gear wheel, and a dash-pot having a plunger connected and movable with said rack.

5. In an automatic telephone responder, the combination with a rotary record support comprising a rotary shaft and a head revoluble on said shaft and adapted to carry 100 a record, of means for rotating said shaft in one direction, electro-magnetically controlled means for engaging said head to hold it from rotating, a collar having a peripheral notch secured to said shaft, a pawl pivoted to said head and adapted to enter said 105 notch, a gear wheel rotatable on said shaft, a pawl carried by said shaft and adapted to engage and carry with it said gear wheel, means for disengaging the second named pawl from said gear wheel, once during 110 each revolution of the shaft, a dash-pot having a reciprocative plunger, and a rack meshing with said gear wheel and connected to and movable with said plunger.

In testimony whereof we have signed our 115 names to this specification.

MARY BASSETT HAMACHER.

IGNATIUS McCUTCHAN.
